US00D619845S

(12) **United States Design Patent**
Gelardi et al.

(10) **Patent No.:** US D619,845 S
(45) **Date of Patent:** ** Jul. 20, 2010

(54) **DISC PACKAGE**

(75) Inventors: **John A. Gelardi**, Wake Forest, NC (US);
Kenny Freitag, Cheshire, MA (US);
Andrew Siditsky, Simi Valley, CA (US)

(73) Assignee: **MeadWestvaco Corporation**,
Richmond, VA (US)

(**) Term: **14 Years**

(21) Appl. No.: **29/320,183**

(22) Filed: **Jun. 23, 2008**

Related U.S. Application Data

(63) Continuation of application No. 29/275,340, filed on Dec. 21, 2006, now Pat. No. Des. 573,831, and a continuation of application No. 29/275,341, filed on Dec. 21, 2006, now Pat. No. Des. 572,962, and a continuation of application No. 29/275,342, filed on Dec. 21, 2006, now Pat. No. Des. 572,963, and a continuation of application No. 29/275,343, filed on Dec. 21, 2006, now Pat. No. Des. 572,964, and a continuation of application No. 29/275,344, filed on Dec. 21, 2006, now abandoned, said application No. 29/275,340 is a continuation of application No. 29/246,672, filed on May 2, 2006, now Pat. No. Des. 563,141, said application No. 29/275,344 and a continuation of application No. 29/251,743, filed on Jan. 12, 2006, now Pat. No. Des. 557,546.

(57) **CLAIM**

The ornamental design for a disc package, as shown and described.

DESCRIPTION

FIG. 1 is a perspective view of a disc package showing our new design;

FIG. 2 is a top plan view thereof;

FIG. 3 is an interior plan view thereof, in an opened position; and,

FIG. 4 is an interior perspective view thereof.

The dash-dash broken lines which illustrate unclaimed structure and the dot-dash broken lines which define the bounds of the claimed design form no part thereof.

1 Claim, 4 Drawing Sheets
